APPARATUS FOR OPENING AND CLOSING
DOORS

Hoke Woodward, Los Angeles, Calif.

Application June 1, 1936, Serial No. 82,725

7 Claims. (Cl. 268—30)

This invention relates to an invention for opening and closing doors, and more particularly to an apparatus for opening and closing heavy doors such, for example, as garage doors.

Many types of garage doors of the so-called overhead type have been developed and are now in general use. These overhead doors are generally of two types, that is, one which is operated through a counterweight so that the weight of the door is balanced permitting the door to be swung into open or closed position easily, and secondly, wherein the counterweighting of the door is performed through spring means which act equivalent to the counterweight.

Many forms of opening or closing devices have been suggested for use in connection with the doors generally and there has been for some period of time a particular demand for a device which might be conveniently and easily adapted to a door for opening and closing the door automatically or from a point remote from the door itself.

It is an object of this invention to provide a device for opening and closing doors wherein a measured quantity of water is utilized for the moving of the door to the desired position to overcome the effect of a counterweight or spring and which quantity of water is then disposed of to permit the counterweight or springs to return the door to the opposite position.

It is a further object of this invention to provide a means wherein a door such, for example, as a garage door, may be opened or closed due to the addition of a balancing mechanism of such a door by a measured quantity of water to move the door in the desired direction, and which quantity of water may be disposed of after the door is moved to the desired position permitting the door to return to the opposite position and in which construction means are provided for permitting the said door opening and closing means to be actuated at a point remote from the door.

Other objects and advantages of this invention it is believed will be apparent from the following detailed description of a preferred embodiment thereof as illustrated in the accompanying drawings.

In the drawings:

Figure 1 is a diagrammatic view of a door and door actuating mechanism embodying my invention.

Figure 2 is an elevation partly in vertical section thereof.

Figure 3 is a sectional end elevation taken substantially on the line 3—3 of Figure 2.

Figure 4 is a sectional plan view taken substantially on the line 4—4 of Figure 2.

Figure 5 is an enlarged fragmental detail partly in vertical section.

Figure 6 is a further enlarged fragmental detail partly in section illustrating one form of latch means which may be embodied in my invention.

In the drawings 1 indicates a door of the overhead type and as herein illustrated, the door 1 is of the counterweighted type, but it is obvious that my invention is equally applicable to other forms of balanced or over-balanced doors wherein either counterweights or springs are utilized for balancing the door or may be utilized for moving the door to one of its desired positions.

The door 1 is indicated as applied to a garage 2 or other outbuilding. The means for actuating the door 1 embodying my invention may be controlled by a means 3 upon a post 4 located at any desired position either within or exterior to the dwelling or house with which the outbuilding is connected and at a point where it may be readily accessible from a motor vehicle approaching the outbuilding 2 as an example.

The door 1 in the particular illustration of the counterbalanced door herein set forth is connected to brackets 5 at its opposite sides, and the brackets 5 are journaled on trunnions 6 carried within the structure of the building 2. An arm 7 extends rearwardly from the trunnion 6 and is provided with counterweights 8 which may if desired be adjustably secured to the arm 7 by means of set screws 9.

Ordinarily as constructed, the counterweights 8 are positioned upon the arm 7 in such position as to balance the weight of the door 1 and the brackets 5 so that an operator of the door, by the exercise of a little energy, may move the door to or from closed position. In accordance with my invention, the counterweight 8 or the spring used in a similar position is utilized for moving the door to one of its desired positions, for example, to the open position indicated in dotted lines in Figure 2 of this embodiment of my invention.

In order to move the door to the opposite or closed position, I provide upon the door 1 a closed water container 10 into which a measured quantity of water is introduced when it is desired to close the door through a connection 11 leading from any suitable source of water supply. As herein illustrated for the purpose of convenience, the water supply pipe 11 is adapted to one of the brackets 5 and extends downwardly into the

water container 10. The means for controlling the admission of water into the container 10 from the supply pipe 11 may be suitably located at any desired position as, for example, upon the post 4 at a point remote from the building 2 where it may be actuated for example from the seat of a motor vehicle when the motor vehicle approaches or is leaving the garage or building 2.

In order to permit the door to return to the opposite or open position after water has been admitted into the container 10, a valve 12 is provided in the container 10, which valve 12 may be normally held in closed position by means of a spring 13. In order to discharge the water from the container 10 to permit the door 1 to return to the open position, a valve contacting member 14 is mounted in position to engage the stem 15 of the valve 12. The valve contacting member 14 may be, as illustrated, a perforated guard for a sewer outlet 16 into which the water from the container 10 is discharged when the door 1 is closed. As so far indicated, the admission of water into the container would cause the door to close and as the door is closed and the valve 13 is opened, the counterweight 8 would again open the door. In order to maintain the door in closed position against the effect of the counterweight 8, a latch of any desired character may be employed. One form of such latch is indicated as of the remote control type. In order to avoid the necessity of providing in such a structure an additional lock, the latch 17 may be located upon the inside of the garage 2 in position to latch the garage door 1 in closed position when moved to closed position under the influence of the water admitted into the container 10.

The latch 17 is generally of the spring plunger type, the plunger of which is adapted to engage within a latch recess 18 formed in the door 1 and to remain in the latched position until actuated by some exterior means.

I have indicated diagrammatically a solenoid actuated type of valve, the solenoid of which is connected by means of current supply lines 20 to a switch 21 mounted on the post 4 in the same position as the control means for the water supply line 11. The latch is indicated in position to engage the upper end of the door but might be positioned in any other desired point.

The operation of the opening and closing device embodying my invention is: With the door closed in the position indicated in Figure 2, and when it is desired to open the door 1, the latch 17 is released by completing the current supply to the solenoid which actuates the latch plunger, thereby withdrawing the plunger of the latch from the recess 18. The counterweight 8 then causes the door to rise from the full line position of Figure 1 to the dotted line position, and the motor vehicle or other device enters the garage.

The operator on leaving the garage opens the valve supplying the water to the container 10 and the door slowly closes as the water overcomes the influence of the weight 8. When the door moves to the closed position, the valve stem 15 engages the valve opener 14 discharging the water from the container 10 into the sewer opening 16 and the latch 17 again engages to hold the door in closed position.

It will be obvious that my invention is equally applicable to other types of doors than those as herein specifically illustrated. For example, other types of counterbalance doors which move upwardly rather than around a pivot support

and which doors are balanced by weights or springs to enable them to be easily actuated.

Having fully described my invention, it is to be understood that I do not wish to be limited to the details herein set forth, but my invention is of the full scope of the appended claims.

I claim:

1. In a garage door structure, the combination of a door, means for pivotally supporting the door to permit the door to swing to and from closed position, means normally maintaining the door in one position, a closed water container, and means for supplying water to the container to move the door to the other position, a valve in the water container, and means at the second position of the door to engage and open the valve to discharge the water from the container.

2. In a door structure, the combination of a door of the overhead swinging type, pivot means permitting the door to swing to and from overhead position, overbalancing means for swinging the door around said pivot to one position, means adapted to receive water to overweight the door with reference to said overbalancing means to cause the door to swing to a second position, water discharge means in the water receiving means, means for actuating the latter said means to discharge the water from the receiving means, means to hold the door in the second position against the tendency of the overbalancing means to swing the door to the first position, and a control means remotely positioned with reference to said door for controlling the latch means and the supply of water to the water receiving means.

3. In a door structure, the combination of a door of the overhead swinging type, pivot means permitting the door to swing to and from overhead position, overbalancing means for swinging the door around said means to one position, means adapted to receive water to overweight the door with reference to said overbalancing means to cause the door to swing to a second position, and means operating automatically when the door reaches the second position to discharge the water from the water receiving means.

4. In a garage door structure, the combination of a door, means for pivotally supporting the door to permit the door to swing to and from closed position, means normally maintaining the door in one position, a closed water container, and means for supplying water to the container to move the door to the other position, a valve in the water container, and means at the second position of the door to engage and open automatically the valve to discharge the water from the container.

5. In a garage door structure, the combination of a door hanger, means for pivotally supporting the door to permit the door to swing to and from closed position, means normally maintaining the door in one position, a closed water container, means for supplying water to the container to move the door to the other position, a valved outlet in the water container, latch means for holding the door in the second said position, and means adapted to be actuated when the door moves to the latter said position to open automatically the valve outlet and permit the water to be discharged from the container after the latch means is engaged.

6. In a door structure, the combination of a door of the overhead swinging type, means for supporting the door to permit the same to swing to and from overhead position, overbalancing

means for swinging the door to the overhead position, a container secured to the door to receive and retain water to cause the door to move to the closed position, the closed container having a normally closed valve outlet, and means for automatically opening the valve outlet when the door is in the second position, and means for retaining the door in the closed position.

7. In a door structure, the combination of a door of the overhead swinging type, means for supporting the door to permit the same to swing to and from overhead position, overbalancing

means for swinging the door to the overhead position, a container secured to the door near the lower edge thereof, said container being adapted to receive and retain water therein, means for supplying water to the container, a normally closed valve in the container, a water disposal means at approximately the position of the door in closed position, and means for automatically actuating the valve of the container to discharge the water from the container to the water disposal means. 5

HOKE WOODWARD. 10
